US00D773241S

(12) **United States Design Patent** (10) **Patent No.:** **US D773,241 S**
Arseneau et al. (45) **Date of Patent:** **** Dec. 6, 2016**

(54) **HANDLE PORTION**

(71) Applicants: **Allen Arseneau**, Hingham, MA (US);
Diana Arseneau, Hingham, MA (US)

(72) Inventors: **Allen Arseneau**, Hingham, MA (US);
Diana Arseneau, Hingham, MA (US)

(**) Term: **15 Years**

(21) Appl. No.: **29/539,430**

(22) Filed: **Sep. 14, 2015**

Related U.S. Application Data

(63) Continuation of application No. 29/516,541, filed on Feb. 3, 2015, now Pat. No. Des. 757,499, and a continuation of application No. 14/279,908, filed on May 16, 2014.

(57)

CLAIM

The ornamental design for a handle portion, as shown and described.

DESCRIPTION

FIG. 1 is a top perspective view of a handle portion showing our new design;

FIG. 2 is a right side view thereof;

(Continued)

FIG. 3 is a front view thereof;
FIG. 4 is a rear view thereof;
FIG. 5 is a front view thereof in use with an alternative cup;
and,
FIG. 6 is a front view thereof in use with a knife.
The broken lines in the drawing depict environmental subject matter only and form no part of the claimed design.
